UNITED STATES PATENT OFFICE.

JAMES BURLINGTON RIGG, OF OAK PARK, ILLINOIS.

MEANS FOR AND METHOD OF REGULATING BREATHING FOR SINGING AND WIND-INSTRUMENT PRACTICE.

1,354,212.

Specification of Letters Patent. Patented Sept. 28, 1920.

Application filed February 9, 1920. Serial No. 357,117.

To all whom it may concern:

Be it known that I, JAMES BURLINGTON RIGG, a subject of the King of Great Britain, residing at Oak Park, in the county 5 of Cook and State of Illinois, have invented a new and useful Improvement in Means for and Methods of Regulating Breathing for Singing and Wind-Instrument Practice, of which the following is a specification.

10 The primary object of my invention is to facilitate exercise in breathing for acquiring such control of breath-exhalation as will induce habitual correct breathing in singing, wind-instrument-playing, and the 15 like (including whistling).

Having primarily devised my improvement for training to acquire the habit of correct breathing in singing, the following description is confined to that particular 20 use thereof, though its advantages are to be understood as extending to all desirable breath-controlling exercise, incidentally including lung-development, though in accomplishing this incidental object my invention 25 is not to be confounded with instrumentalities designed for that specific purpose nor for measuring lung-exhaling power.

In the accompanying drawing, Figure 1 is a view in elevation of my exercising apparatus, showing the preferred construction 30 thereof for its purpose, and Fig. 2 is an enlarged broken sectional view of the same.

A breath-receptacle 3, preferably in the form of a cylindrical tube of transparent 35 glass, and having an open upper end, rises from a standard 4, which may also be of glass and integral with the tube, the bottom 5 of which is shown to slope downwardly, for drainage, to a nipple 6 having removably 40 attached to it a flexible tube 7, such as rubber hose, terminating in a mouthpiece 8. The upper end of the cylindrical tube 3 is open to substantially the full extent of the interior diameter of said tube, thus affording 45 free egress to the exhaled breath passing upward between the body 9 and the wall of said tube.

At suitable intervals on the tube 3 are provided appropriate marks to indicate to 50 the user the amount of breath to be expended in producing different tonal effects. The markings shown are, at rising intervals, "P P-1," denoting pianissimo and the first gradation; "P-2," denoting piano and the 55 second gradation; "M P-3," denoting

mezzo piano and the third gradation; "M F-4," denoting mezzo forte and the fourth gradation; "F-5," denoting forte and the fifth gradation; "F F-6," denoting fortissimo and the sixth gradation. 60

In the tube 3 is reciprocably confined a body 9, to be raised by breath-pressure directed against it from underneath into the tube and to descend by reduction or exhaustion of such pressure as and for the purpose 65 hereinafter explained. The form of the body 9 found to be most desirable for its purpose is that of a hollow cylinder, which should be of very light sheet-metal, preferably aluminum, having a closed lower and 70 an open upper end and somewhat shorter than the tube 3, which it fits snugly to be freely reciprocated piston-like therein, but not so snugly as to prevent necessary venting along its exterior, through the open 75 upper end of the receiving tube 3, of the breath of the user introduced into the latter through the hose 7. As will be seen, when the device is in use the body 9 is surrounded by the air from the exhalation of the user 80 causing the said member to float on the body of air, thus giving said member a buoyancy and lightness rendering it peculiarly sensitive to changes in the breath-pressure actuating the same. 85

To exercise with the described apparatus, the user having inhaled, exhales (as in the act of singing a tone and enunciating, say, "oo—oo—oo," to properly direct the tone forwardly), through the mouthpiece 8 and 90 hose into the tube 3, with the gradation-marks thereon facing him, or, in view, and thus directs the breath-pressure against the closed lower end of the tube 9 to raise the latter, with the endeavor, which acquires 95 certainty of accomplishment with practice, of expending only sufficient breath from each inhalation to raise the body 9 into registration at its lower end with the prescribed or predetermined gradation-marking on the breath-receiving tube. The exhalation should be so timed, as by a certain number of regular beats, such as those of a metronome, as not only to cause the body 9 to attain such registering position, but also 100 to maintain it for a predetermined time. With practice, the user acquires the habit of so controllably economizing exhalation as to produce from each inhalation an even and smoothly sustained tone, in singing, 110

- from the beginning of exhalation to the predetermined point of thereby raising the body 9; in the same way the user may practice regulation of exhalation to reciprocate the body 9 between gradations on the tube 3, for attaining steady crescendo and diminuendo tonal effects—in all instances without "running short of breath," or taking breath spasmodically and thus interrupting a tone to be sustained or a word or phrase to be sung on such sustained tone. Moreover, practice with the apparatus induces the desirable deep-breathing habit—deep inhale and slow exhale—even in walking, with resultant physical benefit.

The purpose of providing the member 9 as a hollow body, besides that of lightness, is to adapt it to be weighted, as by introducing water or other medium into it for users desiring to exercise exhaling with greater force, requiring increased resistance.

The apparatus, as shown, is desirably hygienic, the parts being readily separable for cleaning.

I claim:

1. The practice-method of controllably regulating breathing, which consists in forcibly exhaling and directing the breath under confinement into a receptacle underneath a body reciprocably confined therein to move said body and cause it to float and to be maintained on the body of air from the breath and at predetermined elevations, and simultaneously venting the air from the receptacle.

2. Practice-apparatus for controllably regulating breathing, comprising a breath-receptacle provided with an inlet and an outlet, said outlet being of a size substantially equal to the interior diameter of said receptacle, a tube leading to said inlet, and a resistance-body reciprocably confined in said receptacle to extend and be movable bodily therein from above said inlet, the opposing walls of said receptacle and body forming between them venting space for the exhaled breath in open communication with said inlet.

3. Practice-apparatus for controllably regulating breathing, comprising a breath-receptacle provided with an inlet and an outlet, said outlet being of a size substantially equal to the interior diameter of said receptacle, and with gradation-marks at intervals, a breath-directing tube leading to said inlet, and a resistance-body reciprocably confined in said receptacle and exposed to breath-pressure directed against it from underneath through said inlet, the opposing walls of said receptacle and body forming between them venting space for the exhaled breath in open communication with said inlet.

4. Practice-apparatus for controllably regulating breathing, comprising a tubular breath-receptacle having an outlet of a size substantially equal to the interior diameter of said receptacle, an inlet, a breath-directing tube leading to said inlet, and a resistance-body reciprocably confined in said receptacle and having its under surface exposed to breath-pressure directed against it through said inlet, the opposing walls of said receptacle and body forming between them venting space for the exhaled breath in open communication with said inlet.

5. Practice-apparatus for controllably regulating breathing, comprising an upright transparent tube having a lower inlet, a breath-directing tube leading to said inlet, and an opaque resistance-body reciprocably confined in said upright tube and having its under surface exposed to breath-pressure directed against it through said inlet, the opposing walls of said receptacle and body forming between them venting space for the exhaled breath in open communication with said inlet.

6. Practice-apparatus for controllably regulating breathing, comprising a transparent upright cylindrical tube having an open upper end substantially equal to the interior diameter and an inlet near its lower end, and provided with gradation-marks at intervals, a breath-directing tube leading to said inlet, and a resistance-body reciprocably confined in said transparent tube to be raised therein by breath-pressure directed against it through said inlet, the opposing walls of said receptacle and body forming between them venting space for the exhaled breath in open communication with said inlet.

7. Practice-apparatus for controllably regulating breathing, comprising an upright cylindrical tube having an open upper end substantially equal to the interior diameter and an inlet near its lower end, a breath-directing tube leading to said inlet, and a cylindrical resistance-body reciprocably fitting within said upright tube to be raised therein by breath-pressure directed against it through said inlet, the opposing walls of said receptacle and body forming between them venting space for the exhaled breath in open communication with said inlet.

8. Practice-apparatus for controllably regulating breathing, comprising an upright cylindrical tube having an open upper end substantially equal to the interior diameter and an inlet at its lower end, a breath-directing tube leading to said inlet, and a hollow cylindrical resistance-body having a closed lower end and fitting within said upright tube to be raised therein by breath-pressure directed against said closed end through said inlet, the opposing walls of

said receptacle and body forming between them venting space for the exhaled breath in open communication with said inlet.

9. Practice - apparatus for controllably regulating breathing, comprising an upright cylindrical transparent tube having a supporting standard, an open upper end and an inlet near its lower end and provided with gradation-marks at intervals, a breath-directing tube leading to said inlet, and an opaque cylinder reciprocably fitting within said transparent tube to be raised therein by breath-pressure directed against its lower end through said inlet, the opposing walls of said receptacle and body forming between them venting space for the exhaled breath in open communication with said inlet. 15

10 recting tube leading to said inlet, and an

JAMES BURLINGTON RIGG.
